ATTORNEY.

UNITED STATES PATENT OFFICE.

SAMUEL M. EISNER, OF NEWARK, NEW JERSEY.

ALARM DEVICE.

1,372,678.

Specification of Letters Patent. Patented Mar. 29, 1921.

Application filed October 7, 1919. Serial No. 329,018.

To all whom it may concern:

Be it known that I, SAMUEL M. EISNER, a citizen of the United States, and a resident of Newark, county of Essex, and State of New Jersey, have invented certain new and useful Improvements in Alarm Devices, of which the following is a specification.

This invention relates to an alarm device to prevent the theft of automobiles, and it is described as being applied to automobiles, although it will be understood that it is adapted for other applications.

The invention consists of a device to be placed in the electrical circuits of an automobile, and having a switch mechanism for the ignition system and also having an alarm circuit the invention comprising a device for locking or releasing the switch arm at will and also actuating a make-and-break device so that, according to the position of the lock, the ignition system is operative or the alarm circuit is made operative. When the alarm circuit is made, the ignition is broken, and neither the alarm circuit nor the ignition circuit can be changed from this status without the positive operation of the lock.

The invention is illustrated in the accompanying drawing, in which Figure 1 is a back view of the casing, with the back removed, showing the mechanism within the switch box, and Fig. 2 is a section on line 2-2 in Fig. 1. Fig. 3 is a detail view showing a modified manner of wiring.

In the drawing 10 indicates, in general, the terminal of the ignition system, which is grounded and is usually the spark plug in the cylinder, the wires 11 and 12, connected by the switch 13, leading to the switch box, and the second wire 14 leading to a source of electrical energy, such as a storage battery 15, which is also grounded, and when the circuit is closed, it makes ignition possible in the engine.

The alarm circuit comprises a wire 16 in circuit with an alarm device 17; this device being also grounded, usually to the body of the vehicle, and the other wire 18 being connected, in the case of Ford or similar cars, to a dry battery 19. In other instances where the dry batteries are not used, a wire 20 connects the terminals 27 and 29 and in this way the storage battery 15 is adapted to energize both circuits.

The casing 21 is suitably disposed, usually on the dashboard of the vehicle, and

contains a switch arm 22 which is adapted to swing, in the manner shown being mounted on a pivot 23 and having one end 24 secured to a spring 25, which has a tendency 60 to pull the switch arm in one direction.

The wires 12 and 14 are connected to the terminals 26 and 27, and the wires 16 and 18 are connected to the terminals 28 and 29, the switch arm having its end 30 arranged 65 to contact with these terminals and connect them electrically. The end 31 of the switch arm is held against action by the spring 25 by means of a latch 32, which is normally held in position by a yielding means, such as 70 a spring 33, and the latch 32 has a nose 34 which engages the under side of the end 31 of the switch arm to hold it up.

A suitable lock 35 is mounted in the casing and is of any desired type, being operated 75 by a key 36 and having on the inner end a lock piece 37, which is preferably made of fiber or similar material and is operated by means of the key, and having its outer end adapted to engage either the under side of 80 the end 31 of the switch arm, or to be moved to engage a plate 38 of a make-and-break device within the circuit comprising a connection 39 from the terminal 40 to the contact 41; the plate 38 being connected by a wire 42 85 to a magnet 43, which magnet is adapted to operate on the latch 32, the magnet, in turn, being grounded through the wire 44 so as to complete the circuit.

The switch 13 is usually a starting switch, 90 that is, it is thrown on when a driver is to start his car, and when the device is locked, as shown in Fig. 1, when the switch 13 is thrown on, the current can pass through the battery 15 into the ignition system indicated 95 at 10 and the machine is in condition to be started. If, however, the operator has unlocked the device, so that the lock piece 37 is horizontal, the plate 38 of the make-and-break device has been forced against the 100 contact 31, and if the circuit is thrown on by means of the switch 13, the make-and-break device is closed and the magnet 43 is energized, the latch 32 is pulled back and the switch arm is operated by the spring 25, 105 which causes the end 30 of the switch arm to engage the terminals 28 and 29, which connects up the alarm circuit and the alarm is sounded and continues to sound, even if the switch 13 is open, as the opening of the 110 switch 13 in no way affects the operation of the switch arm 22, and the device will con-

tinue to sound until the lock piece 37 is turned. When the lock piece 37 is turned, the make-and-break device 38 is opened and the lock piece acts as a setting device to re-establish the switch arm in its normal position, where it is again engaged and held up by the latch 32.

It will be evident from this description that on the sounding of the alarm, the switch 10 arm is disconnected from the contacts that are part of the ignition circuit, and in the absence of a complete ignition circuit it would be impossible, while the alarm is sounding, to start the engine.

15 I claim:

An alarm device comprising a switch mechanism including terminals for two sepa-

rate circuits, a movable switch member, a latch normally holding the switch member in position to contact with the terminals of 20 one circuit, a magnet for releasing the latch to permit the switch to close the other circuit, a make and break device in the magnet circuit, and lockable means movable from a position in which it closes the magnet circuit 25 at the make and break device and is out of the path of movement of said switch member to an alternative position in which the switch member is in latching position and the magnet circuit is open.

In testimony that I claim the foregoing, I have hereto set my hand, this 29th day of September, 1919.

SAMUEL M. EISNER.
